ELECTRIC ARC LAMP

George E. Inman, Cleveland Heights, and Eugene Lemmers, Cleveland, Ohio, assignors to General Electric Company, a corporation of New York

Application June 23, 1932, Serial No. 618,894

11 Claims. (Cl. 250—35)

Our invention relates to electric arc lamps of the type comprising refractory metal electrodes sealed in a transparent or translucent bulb or other container. One of the objects of our invention is to provide such an arc lamp which will be an efficient source of visible and/or ultra-violet rays and which will operate directly from a line carrying the ordinary commercial voltage without the use of a transformer or other external ballast or equipment. Another object of our invention is to provide a combination of elements in the lamp which will increase the ultra-violet efficiency thereof.

According to our invention a lamp comprising an ultra-violet transmitting bulb is filled with a readily ionizable gas such as argon or neon and contains a pair of special electrodes and a resistance heater. Said heater comprises a coil of refractory wire, connected in series with the arc gap and encased in a refractory and insulating tube which extends adjacent to or through a body of a vaporizable metallic substance, such as mercury or sodium, in said bulb. Said heater is so designed that it will take up the difference in voltage between that on the line and that taken by the arc itself. This energy is not lost because it greatly increases the efficiency of the arc by raising the temperature of the mercury pool to such an extent that the mercury concentration in the vicinity of the arc is very high. Said heater is also a source of visible light and infra-red radiation. The electrodes each comprise a surface coated with a thermionically active compound used in combination with a refractory terminal. Said coated surfaces aid in the starting of the arc wherein a glow or diffuse discharge takes place around the electrodes which concentrates, as the temperature and pressure build up, to an arc which strikes across the refractory terminals, said terminals being directly in the arc path and closer together than said coated surfaces. The heat from the discharge and the heat radiated from the refractory terminals maintain the coated surfaces in an active condition. Said coated surfaces therefore serve the double purpose of facilitating starting and aiding in the maintenance of a high pressure arc. The refractory terminals serve to collect positive ions and consequently protect the coatings. One of the features of our invention is the disposition of the electrodes longitudinally in the bulb and directly in the convection stream of vapor arising from the vaporizable metal body, thereby making possible a comparatively long arc gap and increasing the ultra-violet efficiency.

Other features and advantages of our invention will appear from the following detailed description of species thereof and from the drawing.

In the drawing Fig. 1 is a perspective view of a lamp comprising our invention; Fig. 2 is a horizontal sectional view of one form of main and auxiliary electrodes; Fig. 3 is a diagrammatic representation of the circuit of the lamp; and Fig. 4 is an enlarged perspective view of a modification of an electrode.

Referring to Fig. 1, the lamp comprises a base 10 and bulb 11 filled with a readily ionizable gas such as argon or neon. A combination electrode comprising a metal member such as a tube 12, preferably of nickel, is mounted on a leading-in wire 13 which is sealed in a stem tube 14. Instead of the tube 12, a disc or cup may also be used. Said tube 12 has a coating of a thermionically active compound (Fig. 2), preferably an alkaline earth metal compound such as barium oxide on the surface thereof. The tube 12 as shown in the drawing may be closed at the upper end and mounted thereby on the wire 13. Said electrode comprises also a wire 15 extending through said tube 12 and connected thereto at the closed end and carrying a terminal 16 comprising a ball or block of tungsten or other refractory metal which is located just beyond the edge of the tube 12. Said tube 12 may be made of tungsten or Konel metal and in addition to barium oxide the coating thereon may comprise strontium or calcium oxides or combinations thereof.

A second combination electrode comprising a tube 17 and terminal 18, similar to 12—16, is located near the bottom of the bulb 11, both of said electrodes in the form shown being located substantially in the axis of said bulb. Said electrode 17—18 is mounted on a lead wire 19 which is sealed in the stem tube 14 and is enclosed for nearly its whole length in a quartz tube 20. A third electrode which may be added to facilitate starting comprises a metal body, preferably a tube 21 which also has a coating of a thermionically active compound on the surface thereof. Said tube 21 is mounted very close to tube 12 on a lead wire 22 sealed in the stem tube 14. A heater comprising a coil 23 preferably of tungsten or nichrome is mounted on lead wires 24, 25 which are sealed in the stem tube 14. Said heater 23 is encased in a refractory tube 26, preferably of beryllium oxide, which is formed into substantially a U-shape, the legs of the U extending along the gap between the electrodes and the bent portion passing between the electrode 17—18 and the end of the bulb 11. Said bent portion of tube

26 passes adjacent to or preferably through a pool of mercury 27 located in the bulb 11. Said tube 26 is heated to a bright red by the heater 23 thus increasing the vaporization of mercury from the pool 27 and greatly increasing the concentration of mercury vapor in the region of the arc which is located directly over the heated pool. The ultra-violet efficiency increases rapidly with increasing mercury vapor concentration. Short 10 glass tubes 28, 29 are mounted over the ends of said tube 26 and extend around the leads 24, 25 to the stem tube 14 to which they may be sealed, thereby preventing the formation of an arc at said lead wires 24, 25. Although beryllium oxide 15 is to be preferred for the tube 26, other refractory substances may be used, such as thoria, alumina or magnesia. The lower electrode 17-18 may support the tube 26 by means of a wire 30 coiled thereabout and sealed in a glass 20 bead 31. A short wire support 32 is also sealed in the bead 31 and is mounted on the lead wire 19.

Referring to Fig. 3, the preferred circuit through the lamp is from leading-in wire 24 through the heater and ballast resistance 23, lead 25 wire 25, through a relatively high resistance 33 (located in the base 10), lead wire 22, starting electrode 21, upper electrode 12-16 and leading-in wire 13. At the start, a glow discharge takes place between the auxiliary electrode 21 and the 30 tube 12 and a second glow discharge takes place around the lower electrode tube 17 which is connected by the lead wire 19 to the wire 25. Said discharges increase in size and strength as the temperature and pressure build up within the 35 lamp until an arc discharge is formed which strikes across terminals 16, 18 since they are closer together than the tubes 12, 17. When the arc has formed, the resistance 33 and electrode 21 are substantially cut out of the circuit, practically 40 all the current going through the arc. It is possible, with the proper combination of purity and composition of gas and proper activity of electrode surfaces, to dispense with the auxiliary electrode 21 and cause an arc to strike directly 45 across the main electrodes.

45 A modified construction for the electrodes is shown in Fig. 4 and comprises a support wire 34 carrying a ball or block 35, preferably of tungsten, on the end thereof. A coiled wire 36, also 50 preferably of tungsten, is wound around the support wire 34, thus forming a coiled coil, and may be spot welded thereto at each end. To provide more surface we prefer to wind a plurality of layers of coil 36, three being shown in the figure. The coil 36 is then dipped in a solution of a thermionically active compound, such as barium carbonate, and the ball 35 is wiped clean. A length 55 of wire 37 is then wound about the support wire 34 immediately below the coiled coil 36 and the resulting helix is enlarged so as to surround said coiled coil, being spaced therefrom. After the electrode has been mounted in the lamp and during the process of evacuation, said lamp is inserted in an induction coil and the helix 37 becomes 60 intensely heated, thereby driving carbon dioxide out of the barium carbonate with which the coiled coil 36 has been impregnated, leaving a deposit of barium oxide thereon.

What we claim as new and desire to secure by

70 Letters Patent of the United States is:

1. An enclosed arc device comprising a bulb, refractory metal electrodes in said bulb, a coating of a thermionically active material on said electrodes, a quantity of vaporizable metal in said bulb, and a resistance in series with one of said

electrodes having a covering of refractory insulating material extending through said vaporizable metal.

2. An enclosed arc device comprising a bulb, refractory metal electrodes in said bulb, a coating of a thermionically active material on said electrodes, a quantity of mercury in said bulb, and a resistance in series with one of said electrodes having a covering of refractory insulating material extending through said mercury. 10

3. An enclosed arc device comprising a bulb containing an ionizable medium, a pair of main refractory metal electrodes in said bulb each having a coating of a thermionically active material, a resistance in series with one of said main electrodes and an auxiliary electrode mounted adjacent to but spaced from the other of said main electrodes, said auxiliary electrode being connected to the first of said main electrodes and having a resistance in series therewith. 15

4. An enclosed arc device comprising a bulb containing an ionizable medium, a pair of main refractory metal electrodes in said bulb each having a coating of a thermionically active material, a resistance in series with one of said main electrodes and an auxiliary electrode mounted adjacent to but spaced from the other of said main electrodes, a coating of a thermionically active material on said auxiliary electrode, said auxiliary electrode being connected to the first of said main electrodes and having a resistance in series therewith. 20

5. In a device of the class described, an electrode comprising a support wire, a winding of coiled wire about a portion of said support wire 35 adjacent to the end thereof, a thermionically active compound disposed in the turns of said coiled wire, and a tube surrounding said winding of coiled wire, said tube being mounted on said support wire. 40

6. In a device of the class described, an electrode comprising a support wire, a winding of coiled wire about a portion of said support wire adjacent to the end thereof, a thermionically active alkaline earth metal compound disposed 45 in the turns of said coiled wire, and a helix of wire surrounding said winding of coiled wire, said helix being mounted on said support wire and being spaced from said winding of coiled wire. 50

7. An electric lamp of the high pressure concentrated arc type comprising a bulb, a quantity of vaporizable metal in said bulb, a pair of spaced refractory metal electrodes in said bulb having associated therewith a thermionically active material for initiating an electric discharge, a substantially U-shaped resistance heater in said bulb having a covering of insulating material thereon, the legs of said U extending along the arc gap between said electrodes on opposite sides thereof 55 and the connecting portion of said legs extending adjacent said vaporizable metal so as to heat the said vaporizable metal and increase the concentration of the vapor thereof in the arc gap during the operation of the lamp, said electrodes being so disposed that the arc gap therebetween 60 extends longitudinally of said bulb and in the path of vapors volatilized from said vaporizable metal.

8. An electric lamp of the high pressure concentrated arc type comprising a bulb, a quantity of vaporizable metal in said bulb, a pair of spaced refractory metal electrodes in said bulb having associated therewith a thermionically active material for initiating an electric discharge, a ballast 70

resistance heater in said bulb in series with the arc gap between said electrodes, said heater being substantially U-shaped and having a covering of insulating material thereon, the legs of said U extending along the arc gap between said electrodes on opposite sides thereof and the connecting portion of said legs extending adjacent said vaporizable metal so as to heat the said vaporizable metal and increase the concentration of the vapor thereof in the arc gap during the operation of the lamp, said electrodes being so disposed that the arc gap therebetween extends longitudinally of said bulb and in the path of vapors volatilized from said vaporizable metal.

9. An electric lamp of the high pressure concentrated arc type comprising a bulb capable of transmitting both visible and short wave ultraviolet radiation, a quantity of mercury in said bulb, a pair of spaced refractory metal electrodes in said bulb having associated therewith a thermionically active material for initiating an electric discharge, a ballast resistance heater in said bulb in series with the arc gap between said electrodes, said heater being substantially U-shaped and having a covering of insulating material thereon, the legs of said U extending along the arc gap between said electrodes on opposite sides thereof and the connecting portion of said legs extending adjacent said mercury so as to heat the said mercury and increase the concentration of the vapor thereof in the arc gap during the operation of the lamp, said electrodes being so disposed that the arc gap therebetween extends longitudinally of said bulb and in the path of vapors volatilized from said mercury.

10. An electric lamp of the high pressure concentrated arc type comprising a bulb, a quantity of vaporizable metal in said bulb, a pair of spaced refractory metal electrodes in said bulb having associated therewith a thermionically active material for initiating an electric discharge, a substantially U-shaped resistance heater in said bulb having a covering of insulating material thereon, the legs of said U extending along the arc gap between said electrodes on opposite sides thereof and the connecting portion of said legs extending through said vaporizable metal, said electrodes being so disposed that the arc gap therebetween extends longitudinally of said bulb and in the path of vapors volatilized from said vaporizable metal.

11. An electric lamp of the high pressure concentrated arc type comprising a bulb, a quantity of vaporizable metal in said bulb, a pair of spaced refractory metal electrodes in said bulb having associated therewith a thermionically active material for initiating an electric discharge, a ballast resistance heater in said bulb in series with the arc gap between said electrodes, said heater being substantially U-shaped and having a covering of insulating material thereon, the legs of said U extending along the arc gap between said electrodes on opposite sides thereof and the connecting portion of said legs extending through said vaporizable metal, said electrodes being so disposed that the arc gap therebetween extends longitudinally of said bulb and in the path of vapors volatilized from said vaporizable metal.
